Herman Eichenbaum, Rockville Centre, N. Y.

Application April 11, 1951, Serial No. 14,796

Term of patent 3½ years

(Cl. D88—3)

To all whom it may concern:

Be it known that I, Herman Eichenbaum, a citizen of the United States of America and resident of Rockville Centre, in the county of Nassau and State of New York, have invented a new, original, and ornamental Design for an Umbrella, of which the following is a specification, reference being had to the accompanying drawing forming part hereof, in which:

Fig. 1 is a front elevation of an umbrella embodying my new design; and

Fig. 2 is a plan view of the same.

I claim:

The ornamental design for an umbrella, as shown.

HERMAN EICHENBAUM.
